UNITED STATES PATENT OFFICE

161,208

ALPHABET DISH SET

Clark W. Riddle, Provo, Utah

Application August 16, 1948, Serial No. 148,138

Term of patent 3½ years

(Cl. D44—10)

To all whom it may concern:

Be it known that I, Clark W. Riddle, a citizen of the United States, residing at Provo, in the county of Utah and State of Utah, have invented a new, original, and ornamental Design for an Alphabet Dish Set, of which the following is a specification, reference being had to the accompanying drawing, forming part thereof.

Figure 1 is a group top plan view of an alphabet dish set, showing my new design, and

Figures 2 and 3 are cross-sectional views taken for illustrative purposes in the planes of the lines 2—2 and 3—3 respectively, in Figure 1, and showing sectional configurations which are typical to the several dishes in the set.

I claim:

The ornamental design for an alphabet dish set, as shown.

CLARK W. RIDDLE.
